INVENTOR

Eugene V. Myers

By Attorneys,

Frank G. Myers

WITNESS:

Rene Bruine

UNITED STATES PATENT OFFICE.

EUGENE V. MYERS, OF EAST ORANGE, NEW JERSEY, ASSIGNOR TO A. SCHRADER'S SON, INCORPORATED, OF BROOKLYN, NEW YORK, A CORPORATION OF NEW YORK.

DUST-CAP.

1,399,310.

Specification of Letters Patent.

Patented Dec. 6, 1921.

Application filed December 20, 1918. Serial No. 267,701.

To all whom it may concern:

Be it known that I, EUGENE V. MYERS, a citizen of the United States of America, residing at East Orange, in the county of Essex and State of New Jersey, have invented certain new and useful Improvements in Dust-Caps, of which the following is a specification.

This invention relates to dust caps and aims to provide certain improvements therein.

This invention is particularly directed to dust caps of the quick-detachable type, that is to say, caps which are adapted to slide along the tire valve until a final position is approximately reached, after which they are secured in place.

The present invention comprises a cap having movable means which are formed of metal or the like and which are preferably resilient, and having a wedge member adapted to move such means inwardly to grasp the threads of the tire valve. According to the preferred form of present invention, the movable means are in the form of spring arms which are provided with screw-threads which are normally out of engagement with the threads of the valve and the wedge member has a screw-thread connection with the cap proper. The wedge member is also provided with means such as flats adapted to engage the flats of the tire valve so that when the cap proper is rotated, the wedge member is held against turning and a short rotary movement of the cap proper very effectually clamps the device in place or releases the same.

The invention also includes other features of invention which will be hereinafter more fully described.

In the drawings is illustrated one form of the invention.

Figure 1 is an elevation of the cap.

Fig. 2 is an underside view of Fig. 1.

Fig. 3 is an enlarged sectional view showing the cap in diametrical section.

Fig. 4 is an elevation of the bottom portion of the cap proper.

Fig. 5 is an underside view of Fig. 4.

Fig. 6 is a section on the line 6—6 in Fig. 3.

Referring to the drawings let A indicate the cap as a whole which comprises the cap portion B and the wedge portion C. The cap portion B preferably carries with it a

movable member or members shown as a series of movable arms DD, which preferably are spring arms, and preferably formed as a continuation of the upper part of the cap portion. These arms are threaded as shown at E, and normally are expanded sufficiently to slip over the valve casing without engaging the threads.

The foot portion C is formed with a wedge face F adapted to be engaged by the lower ends of the spring arms. Upon such engagement the arms are wedged inwardly to engage the threads of the valve casing. The cap portion and foot portion are formed with interengaging means such as the screw-thread G, by means of which, when the cap portion is rotated relatively to the foot portion, the former travels downwardly to secure the wedging action thus described. To positively hold the wedging portion against rotation, I preferably provide it with flats HH, which are adapted to engage the flats of the tire valve casing. By this means the wedging portion is held positively against rotation, so that mere manipulation of the cap portion by one of the hands of the user effects a positive tightening or loosening movement sufficient to powerfully engage or easily release the cap.

In applying the cap, the latter is slipped down over the valve casing until the bottom wedging member engages the rim nut or felly, whereupon the cap portion B is rotated. This has the effect of advancing the cap portion with relation to the wedging portion. When the wedging portion has operated sufficiently to cause the threads on the spring arm to engage the valve casing, the tendency of the cap portion is to screw downwardly along the valve threads. As the foot portion is rigidly held by the rim nut, its threaded engagement with the cap proper tends to permit the cap to screw downwardly as fast as the pitch of the connecting thread will permit. If the threads E and G are of the same pitch, the foot portion will permit the cap portion to screw downwardly at the same rate as is permitted by the valve threads. If the two threads are of different pitch, a locking action is obtained. If the thread G is a finer thread, the foot portion will be urged forwardly so as to obtain a better clamping action of the foot portion against the rim nut.

While I have shown and described one form of the invention, it is understood that I do not wish to be limited thereto, as various changes may be made therein without departing from the spirit of the invention. It will be also understood that the invention is not limited to dust caps, but may be applied to other devices which it is desired to connect with a valve or other structure.

10 This application is generic to my application No. 267,702, filed December 20, 1918.

What I claim is:—

1. A dust cap for tire valves or the like comprising a cap portion, movable members associated with said cap portion and provided with threads and a wedging member adapted to force said movable members inwardly, and a connection between said cap portion and said wedging member for moving the cap portion longitudinally of the cap as the cap portion is rotated with relation to the wedging member.

2. A dust cap for tire valves or the like comprising a cap portion, movable members associated with said cap portion and provided with threads and a wedging member adapted to force said movable members inwardly, and a connection between said cap portion and said wedging member for moving the cap portion longitudinally as the cap portion is rotated with relation to the wedging member, and said wedging member having means for non-rotatively engaging the casing of the tire valve.

3. A dust cap for tire valves or the like comprising a cap portion integrally formed with screw-threaded spring arms, a wedging member adapted to force said arms inwardly to clamp the screw-threads thereof into engagement with the tire valve casing, and a screwthreaded connection between said wedging member and said cap portion whereby to move the cap portion downwardly when rotated relatively to the wedging portion, and said wedging portion having means to engage the flats of the tire valve whereby to prevent it from rotation relatively to the latter, and said screw-threaded connection comprising threads of different pitch from the threads of the spring arms.

4. A dust cap for tire valves or the like comprising a cap portion formed with screw-threaded spring arms, a wedging member adapted to force said arms inwardly to clamp the screw-threads thereof into engagement with the tire valve casing, and a screw-threaded connection between said wedging member and said cap portion whereby to move the cap portion downwardly when rotated relatively to the wedging portion, and said wedging portion having means to engage the flats of the tire valve whereby to prevent it from rotation relatively to the latter, and said screw-

threaded connection having finer threads than those of the spring arms.

5. A dust cap for tire valves or the like, comprising a cap portion, movable clamping means formed of substantially non-compressible material adapted normally to pass along the body of a tire valve, and operating means for positively forcing said movable means into clamping contact with such tire valve, said cap portion and operating means being relatively rotatable, and said clamping means being operated by such relative rotation.

6. A dust cap for tire valves or the like, comprising a cap portion, movable metallic clamping means adapted normally to pass along the body of a tire valve, and a wedging means having a screw-threaded connection with said cap portion, whereby the latter can rotate relatively thereto, and said movable means being forced by said wedging means into clamping contact with the tire valve upon such rotation.

7. A dust cap for tire valves or the like, comprising a cap portion, movable clamping means formed of substantially non-compressible material and adapted normally to pass along the body of a tire valve, and a wedging means connected to the cap portion, the cap portion being movable rotatively with relation to the wedging means to effect a relative longitudinal movement of said cap portion and wedging means, said clamping means being adapted to be forced by said wedging means through such relative longitudinal movement to clamp the cap to the valve body, and means for preventing unscrewing of the cap as a whole.

8. A dust cap for tire valves or the like, comprising a cap portion, a member associated with said cap portion, and having means for positively preventing its rotation, and means adapted to be positively forced into contracted position about a tire valve to hold the cap in place thereon, said means being operated by the relative rotary movement of said cap portion and member.

9. A device adapted to be attached to a threaded member or the like, comprising two parts, one of which is rotatable relatively to the other, and is adapted to be rotated by hand to connect the device to the threaded member, and a radially contractible means formed of substantially non-compressible material for engaging the threaded member, said means being moved to engage the threaded member by the relative rotation of said parts, effected by the power of the hand applied through said rotating part, and means for positively holding the other of said parts against rotation with respect to the threaded member.

In witness whereof, I have hereunto signed my name.

EUGENE V. MYERS.
